UNITED STATES PATENT OFFICE.

MARCEL ANDRE JULLIEN AND EMILE LOUIS DESSOLLE, OF LEVALLOIS-PERRET, FRANCE.

METHOD OF RENDERING ELECTROLYTIC COPPER HOMOGENEOUS.

No. 897,291.

Specification of Letters Patent.

Patented Sept. 1, 1908.

Original application filed April 4, 1907, Serial No. 366,421. Divided and this application filed December 7, 1907.
Serial No. 405,611.

To all whom it may concern:

Be it known that we, MARCEL ANDRÉ JULLIEN and EMILE LOUIS DESSOLLE, two citizens of the Republic of France, residing at 5 Levallois-Perret, in France, have invented a new and useful Improved Method for Rendering Electrolytic Copper Homogeneous, of which the following is a specification.

This invention relates to a method of rendering electrolytic copper absolutely homogeneous, so that it has the same resistance and the same tensile strength in every direction.

This application is divided from our application filed April 4th, 1907; Serial No. 366,421.

This method chiefly consists in a polishing action effected by means of a suitable apparatus.

20 In the accompanying drawing given by way of example:—Figure 1 is a longitudinal section of an apparatus suitable for carrying out the invention, and Fig. 2 is a cross-section on the line 2—2 of Fig. 1.

25 The apparatus comprises a water-tight wooden case or vat *a* provided inside with two uprights *b* *b* on which rests the spindle *c* of a drum or cylinder *d*. At one end of the said spindle is mounted a kind of tappet or 30 cam *e*, the projection *f* of which engages with a recess in an arm *g* mounted at the end of a driving shaft *h* which passes through one of the sides of the vat *a* and is provided with a stuffing box *i* to prevent leakage. The shaft 35 *h* is provided with an outside driving pulley *j* for rotating the spindle *h* and consequently the cylinder *d*.

Above the vat *a* is arranged a rolling track *k* on which can move a carriage *l* carrying a 40 suitable electric or other motor *m* to the spindle of which is keyed a crank shaft *n*. The said crank shaft is connected by a rod *o* to an oscillating lever *p*, the pivot pin of which is supported on the carriage *l*. At the bottom 45 end of the said lever *p* is arranged a polishing tool *q* adapted to be applied against the cylinder with a suitable pressure.

The vat *a* contains as usual a suitable electrolytic bath, and the copper is deposited 50 in the cylinder *d*, but, as it is being

deposited, the carriage *l* moves longitudinally on its track *k*, the result of which is the movement of the polisher *q* on the cylinder *d*, while at the same time the said polisher receives from the electric motor *m* a reciprocating movement of suitable amplitude. 55

In moving along the cylinder *d*, the polisher *q* describes therefore on the latter a screw thread of a comparatively small pitch, but at the same time it describes in a continuous manner about the said screw a kind of sinusoidal curve. The amplitude of movement of the polisher *q* and the pitch of the screw-thread are fixed in such manner that the spires of the adjoining sinusoids intersect, and that no point of the metal surface produced on the cylinder *d* by the deposit of the electrolytic copper, escapes the action of the polisher, the pressure of which on the cylinder is suitably determined. Experience has shown that electrolytic deposit thus treated acquires an absolute homogeneity, such that the tensile strength and the resistance of the metal are the same in every direction, while in the 70 metal obtained by ordinary processes, the resistance is generally greater in the direction of the rotation than in the longitudinal direction. The copper deposit thus treated can be used for making tubes, plates, etc. 75 The metal thus obtained is much more suitable for the various machining operations than the electrolytic copper obtained by ordinary processes. 80

In the accompanying drawing the polishing tool is shown applied to the upper portion of the cylinder *d*, but it can also move on any generatrix of the said cylinder with the same results. 85

Having now particularly described and 90 ascertained the nature of our said invention and in what manner the same is to be performed, we declare that what we claim is:—

A method of rendering homogeneous electrolytic copper, consisting in the application 95 against the metal electrolytically deposited on a rotary cylinder in the vat, of a polisher having a reciprocating movement, which moves longitudinally on the cylinder in such manner that the polisher describes on the 100

copper deposit not simply a screwthread, but a sinusoidal curve surrounding the spires of the screwthread, and the sinusoidal curves interengaging in such manner that no point of the surface escapes the action of the polisher which is applied to the cylinder with a suitable pressure.

In testimony whereof we have affixed our

names to this specification in the presence of two subscribing witnesses.

MARCEL ANDRÉ JULLIEN.
